UNITED STATES PATENT OFFICE.

ALFRED W. REISER, OF TOLEDO, OHIO, ASSIGNOR TO THE WESTERN GAS FIXTURE COMPANY, OF TOLEDO, OHIO, A CORPORATION OF OHIO.

DESIGN FOR A CHANDELIER CLUSTER-HOOK.

47,620.

Specification for Design.

Patented July 20, 1915.

Application filed April 5, 1915. Serial No. 19,364. Term of patent $3\frac{1}{2}$ years.

To all whom it may concern:

Be it known that I, ALFRED W. REISER, a citizen of the United States, and residing at Toledo, in the county of Lucas, State of Ohio, have invented a new, original, and ornamental Design for a Chandelier Cluster-Hook, of which the following is a specification, reference being had to the accompanying drawing, forming a part thereof.

Figure 1 is a plan view of the chandelier cluster hook showing my design, and Fig. 2 is a side view of the design shown in Fig. 1.

I claim,—

The ornamental design for a chandelier cluster hook as shown.

ALFRED W. REISER.
